UNITED STATES PATENT OFFICE.

ROBERT JAMIESON, OF HOPEDALE, MASSACHUSETTS, ASSIGNOR TO DRAPER COMPANY
OF HOPEDALE, MASSACHUSETTS, A CORPORATION OF MAINE.

FILLING-GUIDE FOR LOOMS.

1,047,945.

Specification of Letters Patent. Patented Dec. 24, 1912.

Application filed July 15, 1912. Serial No. 709,335.

To all whom it may concern:

Be it known that I, ROBERT JAMIESON, a citizen of the United States, and resident of Hopedale, county of Worcester, State of Massachusetts, have invented an Improvement in Filling-Guides for Looms, of which the following description, in connection with the accompanying drawing, is a specification, like characters on the drawing representing like parts.

This invention has for its object the production of efficient and novel means for guiding or controlling the running filling in a loom so that the filling cannot be caught under the filling-fork under certain conditions of operation, particularly when the cloth being woven is narrow relatively to the width of the loom.

It frequently happens that cloth will be woven which is very narrow in proportion to the width of the cloth which could be woven upon a given loom, and when that is the case there is a long stretch of filling between the selvage of the cloth and the shuttle-box. Occasionally this long stretch of filling will throw ahead as the lay beats up and pass under the filling-fork, causing trouble when the filling is caught.

In accordance with my present invention I provide a guide, which is mounted upon a convenient part or adjunct of the lay, preferably the usual shuttle-guard, and extended downward therefrom in front of the shuttle path to the raceway, to interrupt the filling should it tend to throw a head, the guide being set at such a point with relation to the fork that it will prevent the catching of the filling thereunder. The guide is made adjustable laterally so that it can be set in the position best suited to the conditions in any given case.

The novel features of my invention will be fully described in the subjoined specification and particularly pointed out in the following claims.

Figure 1 is a top plan view of a sufficient part of a loom to be understood, with one embodiment of my invention applied thereto; Fig. 2 is an enlarged transverse section thereof on the line 2—2, Fig. 1, looking toward the right.

In the drawing, 1 is the lay, having the usual race-plate 2, reed 3, reed-cap 4, and shuttle-guard 5, and in Fig. 1 the inner ends 55 of the opposite shuttle-boxes 6, 6 are shown,

with the temples 7, 7, the latter being set in to accommodate the cloth being woven, which latter is shown as quite narrow in proportion to the width of the loom.

My invention is applicable to single or double fork looms, and in Fig. 1 I have shown the loom equipped with two filling-forks, indicated at 8, 8, and of any usual or well known structure, forming no part of my invention.

In accordance with my invention I provide a filling guide 9, made of a strip of plate metal, having a flattened upper end or head 10 provided on its under side with a seat 11, Fig. 2, and with an aperture 12.

The seat is adapted to fit over the shuttle-guard 5 and the head is clamped thereto by the plate 13, having a similar and opposed seat 14 for the guard, said plate having a clamping screw 15 extended through the aperture 12 and set up by a nut 16.

In side elevation the guide 9 extends frontward from the head 10 and is then downturned and curved rearwardly at its foot to rest upon the top of the lay at the front edge of the race-plate 2, as clearly shown in Fig. 2. The guide is set laterally at such a point that it will intercept the filling, if thrown forward, at a point near the fork, and will prevent the filling from passing under or catching upon the fork.

From Fig. 2 it will be seen that the filling guide can be set at any desired point between the fork and the selvage of the cloth, to accommodate any of the various conditions which may arise in actual practice.

The shuttle 17 is shown in Fig. 2 in the left hand shuttle-box, the filling 18 extending therefrom to the selvage of the cloth behind the filling guide 9.

As will be apparent the guide is altogether out of the way of the shuttle, the fork, or any of the working parts of the loom, it is not in the way of the weaver, and it is simple, effective, and can be constructed and applied at a very low cost, saving filling breakage and annoying delays.

The shuttle-guard on the reed-cap is a feature common to practically all looms, and it is of sufficient extent to enable the filling guide to be positioned as desired, and for that reason, and because of its convenience, and the readiness with which the guide can be clamped thereupon I prefer to mount the guide on such shuttle-guard.

Having fully described my invention, what I claim as new and desire to secure by Letters Patent is:

1. In a loom, a filling-fork, a lay having a race-plate, and a filling guide mounted rigidly on the lay above the shuttle path near the filling-fork and having a foot depending to and fixedly positioned with relation to the race-plate in front of the shuttle-path, to intercept the filling if thrown forward and thereby to prevent the filling from passing under or catching on the fork, while the shuttle-path is unobstructed at all times.
2. In a loom, a filling-fork, a lay, a longitudinally extended shuttle-guard thereon, a filling guide mounted upon the guard and having a foot depending in front of the shuttle path down to the raceway of the lay, to intercept the filling if thrown forward and prevent the same from passing under the fork, said guide having a head provided with a seat for the guard, a retaining plate having a similar seat, and a clamping device to clamp the head and said plate in place on the guard adjacent the fork.
3. In a loom, a filling-fork, a lay, a filling guide having a depending portion extended down to the path of the shuttle at the front

thereof and fixedly positioned relatively thereto, to intercept the filling if thrown forward while leaving the shuttle path unobstructed at all times, a supporting member for said guide, carried by the lay and located above the path of the shuttle, and a device to clamp said guide rigidly in adjusted position on its support relative to the fork.

4. In a loom, a filling-fork, a lay, a shuttle-guard thereon above and extending longitudinally of the raceway, a filling guide having a seat for the guard, and means to clamp the guide in laterally adjusted position on the guard, the guide having a foot extended downward to the race-way in front of the path of the shuttle, to intercept the filling on the forward beat of the lay and prevent such filling from being thrown forward under the fork.

In testimony whereof, I have signed my name to this specification, in the presence of two subscribing witnesses.

ROBERT JAMIESON.
